UNITED STATES PATENT OFFICE.

WILLIAM HENRY DANIELS, OF SOUTHSEA, ENGLAND.

CONSTRUCTION OF SHIPS, &c.

SPECIFICATION forming part of Letters Patent No. 352,807, dated November 16, 1886.

Application filed February 9, 1886. Serial No. 191,314. (Model.)

To all whom it may concern:

Be it known that I, WILLIAM HENRY DANIELS, a subject of the Queen of England, residing at Southsea, England, have invented 5 certain new and useful Improvements in the Construction of Boats, Ships, and other Navigable Craft, of which the following is a specification.

My invention relates to the construction of 10 the hulls of vessels, and especially to the hulls of sail-boats, and has for its object to furnish a model which shall be speedy and safe, presenting the least possible obstruction to the movement of the boat through the water, and at the same time having a breadth of 15 beam and other peculiarities of construction which render it almost incapable of being capsized.

In the drawings, Figure 1 is a perspective 20 view of the bottom of the boat, the hull being partly upturned to show it. Fig. 2 is a bottom plan view thereof. Fig. 3 is a vertical longitudinal section through the center of the hull taken on the line 3 3 of Fig. 2. Fig. 25 4 is a transverse vertical section on the line 4 4 of Fig. 2. Fig. 5 is a similar section on line 5 5 of Fig. 2. Fig. 6 is a similar section on line 6 6 of Fig. 2; and Fig. 7 is a vertical longitudinal section on the curved line 30 7 7 of Fig. 2, extending from stem to stern, through one of the halves of the hull, the dotted line therethrough indicating the upper line of the trough formed by the junction of said halves.

Like letters of reference mark the same parts 35 in all the figures.

My invention may be said to consist, essentially, of a double-ended or skiff-pointed hull, which, instead of being provided with a central downward-projecting keel, as is used in 40 such constructions, is grooved out from stem to stern, said groove extending from a point slightly below the water-line of the stem to a similar point on the stern, the top line (or 45 bottom when inserted) of said groove being horizontal and but slightly below the water-line, so that there is presented a broad beam to the water and a rising bow and stern, the water in the groove acting in lieu of a keel to

hold to its course, and the rising bow and stern substantially, if not entirely and absolutely, preventing dead-water and forward resistance.

Referring to the drawings by letters, A marks the bow or stem, and B the stern at the deck-line, and A' and B' the same parts at the line of the top of the central inserted groove in the bottom. The line 6 6 in Fig. 3 is the line of greatest beam, and is the line upon which, as before stated, the sectional view, Fig. 7, is drawn. From the points at which this line intersects the side of the boat the sides taper to both bow and stern.

The sectional views in Figs. 5 and 6 would seem to indicate that the hull is composed of 65 two separate narrow hulls secured together; but such is not the case, as may be seen by reference to the other figures.

Figs. 1 and 2 show that the bow and stern are shaped down to the points A' and B', as though no division whatever existed. From and included in a curved line on each side of the bottom connecting these points is the bottom of the hull, which has a straight groove, C, extending from A' to B', the portion of the 70 hull left out or removed being substantially that of an inverted keel, as may be plainly seen by reference to the dotted lines in Figs. 5 and 6, in which figures the similarity in 75 contour of the groove C and the part indicated in dotted lines below dotted lines c c is very plainly shown. This groove C, when 80 the hull is in the water, will be filled with water, and the effect produced will be similar to that produced in a "catamaran," the 85 body of water acting to hold the boat to its course and prevent drifting. At the same time the draft is very light, the hull sinking in the water just barely over the line A' B'.

The dotted lines in Figs. 5 and 6 are intended to show distinctly the difference between my model and an ordinary single-hull 90 keel-boat.

Having thus fully described my invention, what I claim, and desire to secure by Letters 95 Patent of the United States, is—

A hull for vessels, having its bottom centrally provided with an external inverted-V-

shaped channel or trough, which extends longitudinally through said bottom, and intersects at each end with the stem or cut-water near the water-line, the sides of said channel being curved and merging gradually into the line of curvature of each division of the bottom adjacent to said side, as shown and described.

In testimony whereof I have hereto set my hand in the presence of two subscribing witnesses.

WILLIAM HENRY DANIELS.
